CLAIM

The ornamental design for a jewelry article, as shown and described.

DESCRIPTION

FIG. 1 is a front top perspective view of a first embodiment of a jewelry article showing my new design;

FIG. 2 is rear top perspective view thereof;

FIG. 3 is a front elevation view thereof;

FIG. 4 is rear elevation view thereof;

FIG. 5 is a side view thereof;

FIG. 6 is another side view thereof;

FIG. 7 is a top view thereof;

FIG. 8 is a bottom view thereof;

FIG. 9 is a front top perspective view of a second embodiment of a jewelry article showing my new design;

FIG. 10 is rear top perspective view thereof;

FIG. 11 is a front elevation view thereof;

FIG. 12 is rear elevation view thereof;

FIG. 13 is a side view thereof;

FIG. 14 is another side view thereof;

FIG. 15 is a top view thereof; and,

FIG. 16 is a bottom view thereof.

The broken lines shown immediately adjacent to the shaded areas in FIGS. 1, 2, 7, 9, 10, and 15 represent a boundary of the claim. The other broken lines illustrate environmental subject matter only and form no part of the claimed design.
